UNITED STATES PATENT OFFICE.

EDWARD KILBURN, OF NEW BEDFORD, MASSACHUSETTS.

THREAD-CONTRACTOR FOR SPINNING-MACHINES.

SPECIFICATION forming part of Letters Patent No. 238,595, dated March 8, 1881.

Application filed July 6, 1880. (No model.)

To all whom it may concern:

Be it known that I, EDWARD KILBURN, of New Bedford, county of Bristol, State of Massachusetts, have invented an Improvement in 5 Thread-Contractors for Spinning Machines, of which the following description, in connection with the accompanying drawings, is a specification.

This invention relates to a thread-contractor for spinning-machines, and has for its object 10 to restrain the bowing or throwing out of the thread and obviate the striking together of the threads as they are being spun and wound upon the bobbin.

15 My invention consists in a thread-contractor composed of a piece of wire-like metal coiled at one end to form an open ring or annulus, combined with the hinged guide-board upon which the contractor is secured below the common guide-eye, it co-operating with the ring-traveler and bobbin, as hereinafter more fully described.

20 Figure 1 represents, in section, part of a ring-spinning frame with my improved thread-contractor applied to the hinged guide-board, the dotted lines showing the guide-board thrown up, as is necessary preparatory to doffing or applying bobbins to the spindles; and Fig. 2 is an enlarged top view of the thread-contractor removed from the guide-board.

25 The spindle *a*, bolster *b*, bobbin *c*, ring-rail *d*, ring *e*, traveler *f*, guide-eye *g*, and hinged guide-board *h* are all of usual construction.

30 My thread-contractor *i* is composed, preferably, of a piece of ordinary wire bent to form a large open annulus or ring of about one inch in diameter, the turn of the annulus being a little more than one complete circle, as shown, so as to form a practically continuous wall or 35 surface, against the interior of which the thread may travel without being caught or without liability to escape; yet the annulus is and must be provided with a gap or space to permit thread or yarn to be introduced within 40 the annulus or contractor from its outer side rather than through the same, as would be necessary if the contractor or annulus did not have such an opening in it. The shoulder 45 2 of the contractor, between the annulus or ring 50 part and the upright part or arm 3, serves as a stop to arrest the thread between the guide-eye and bobbin, and cause the thread, as the

bobbin is started, to pass through the gap between the parts 4 5 of and into the annulus, where it will remain so long as the yarn is unbroken. When the yarn breaks, were it not for the gap and the shoulder 2, it would be necessary for the attendant to pass the end of the yarn within the contractor before "piecing" (as it is called) the yarn or connecting its broken 55 ends. The attendant, the yarn having broken, has only to piece or unite the ends in the quickest and easiest way and drop the yarn so pieced, and if it falls on the outer side of the contractor the yarn, during the first rotation 60 of the traveler, will be carried against the shoulder 2 and checked a little, after which it will be immediately drawn through the gap in the contractor and into the interior of the contractor, which will thereafter act to prevent 65 the yarn bowing out, as described.

This thread-contractor presents an annular surface between the guide-eye and top of the bobbin, as shown, to act upon and restrain the bowing or throwing out of the thread at that 70 point, and it so restrains the throwing out of the thread that the threads of adjacent bobbins will not strike together during spinning.

The wire at the upper end of the arm 3 will preferably be curled, as at 8, to form a double 75 loop to receive one of two screws, *l*, by which to attach the thread-contractor to the guide-board.

When the bobbins are to be doffed the guide-board and connected thread-contractors are 80 turned up, as in dotted lines. The contractor 85 *i*, being fixed to the guide-board, and being stationary while the ring-rail rises and falls, acts uniformly as a friction device for the thread, and greatly assists in winding the yarn uniformly and compactly on the bobbin.

90 Were the contractor or annulus fixed to and so as to rise and fall with the ring-rail, it would be practically impossible to piece the ends of the yarn without doffing the bobbin, 95 and when the annulus or contractor happened to be opposite the bobbin the latter could be doffed only by lifting it from the spindle up through the annulus, and to replace the bobbin it would have to be passed down through 100 the annulus.

In this my invention the contractor never surrounds either the bobbin or the spindle, but is always attached to the hinged guide-

board between the usual guide-eye and top of the bobbin, and when the bobbins are to be doffed the contractors and hinged guide-board are quickly removed from above them, as in dotted lines, so as not to be in the way of doffing, the latter operation being done by the attendant in the usual manner practiced in the common spinning-frame where a contractor is not used. The connection of the contractor with the hinged guide-board thus becomes a most essential feature of my invention, and is included in my invention as an essential part.

The contractor during spinning being always stationary with relation with the guide-eye and top of the bobbin makes the thread more uniform as to twist and insures greater evenness in winding than were the contractor connected with and made to rise and fall with the ring-rail, as has been done.

I claim—

The contractor *i*, formed as described, to leave an open space for the insertion of the yarn therein laterally, combined with the hinged guide-board and its guide-eye located above the contractor, and with the ring rail, ²⁵ ring, and traveler, and with the spindle to turn the bobbin upon which the yarn held within the said contractor is being wound, substantially as described.

In testimony whereof I have signed my name ³⁰ to this specification in the presence of two subscribing witnesses.

EDWARD KILBURN.
